SLEEVE BOARD HAVING A LOWERED INOPERATIVE POSITION AND HAVING A RAISED AND LOCKED OPERATIVE POSITION

Max Tronic, Worcester, Mass.

Application March 9, 1946, Serial No. 653,323

1 Claim. (Cl. 38—114)

1

This invention relates to a small ironing board commonly termed a "sleeve board" and used for ironing sleeves, small garments or other similar articles.

It is the general object of my invention to provide an improved sleeve board of the folding type which is simple in construction, economical to manufacture, and reliable and satisfactory in use.

To the attainment of this general object, I have provided a sleeve board which may be very easily and simply raised and locked in ironing position, and which may be unlocked and folded with equal ease and convenience.

My invention further relates to arrangements and combinations of parts which will be herein-after described and more particularly pointed out in the appended claim.

A preferred form of the invention is shown in the drawings, in which

Fig. 1 is a top plan view of a sleeve board embodying my invention;

Fig. 2 is a side elevation, showing the parts in position for use;

Fig. 3 is a view similar to Fig. 2 but showing the board partially folded; and

Fig. 4 is an enlarged detail sectional side elevation to be described.

Referring to the drawings, my improved sleeve board comprises a base 10, a top 11, a pair of links 12, and a brace 14. The base 10 and top 11 are commonly made of wood and may be covered with cloth or any other desired material. These parts are so constructed that the board may be used either side up, according as a larger or smaller surface is desired.

The links 12 are preferably of rectangular form and are pivotally secured to the base 10 and top 11 in parallel relation by staples 16 or other suitable fastening devices. The brace 14 has a U-shaped upper end, as shown at 14a in Fig. 1, and is pivotally secured to the top 11, preferably by staples 17. The lower and free end of the brace 14 is offset or down-turned at an angle of approximately 45° as indicated at 14b (Fig. 4).

A coil spring 20 is mounted on the U-shaped portion 14a of the brace 14, with one end engaging the under side of the top 11 and with the other end extending downward and hooked over the brace 14 as indicated at 20a. The spring 20 is so coiled that the long arm thereof normally tends to unwind clockwise as viewed in Figs. 2 and 3 and thus normally applies a downward tension to the brace 14. The base 10 is provided with a longitudinal groove 24 (Fig. 4) terminating in a vertical recess 25.

2

A locking member 30 (Fig. 4) is pivoted at 31 to the base 10 and is provided with a beveled end face adapted to project over the lower end 14b of the brace 14 when the parts are in the position shown in Fig. 4.

Having described the details of construction of my improved ironing board, the operation and utility thereof will be readily apparent. When the board is in folded condition, the top 11 rests upon the base 10 but is slightly spaced therefrom. To raise the top to ironing position, the operator merely swings the top to the right (as viewed in the drawings), thus giving the links 12 a clockwise motion with respect to the base 10 and swinging the links to the upright position shown in Fig. 2. During such movement, the end 14b of the brace 14 is pushed along the groove 24 and enters the recess 25 as the links 12 reach upright position.

The spring 20 then holds the end of the brace in 20 the recess 25 and for greater security the locking member 30 may be moved from the position shown in Fig. 3 to the position shown in Figs. 2 and 4. In this latter position, the member 30 securely locks the brace 14 in the position shown in 25 Figs. 2 and 4, in which position movement of the top 11 in either direction relative to the base 10 is effectively prevented.

The board may be folded by moving the locking member 30 to the position shown in Fig. 3 and by 30 then pushing the top 11 sharply toward the left, which will dislodge the brace end 14b from the recess 25 and which will thereafter return the parts to folded position.

It will be noted that the spring 20 always presses the end 14b of the brace 14 so that the brace is 35 continuously retained either in the groove 24 or in the recess 25, and no lateral displacement thereof can take place.

When the parts are in the operative position 40 shown in Fig. 2, all parts are rigidly locked and the board may be used either as shown in Fig. 2 or inverted if desired.

Having thus described my invention and the 45 advantages thereof, I do not wish to be limited to the details herein disclosed, otherwise than as set forth in the claim, but what I claim is:

A folding sleeve board comprising a base, a top, links spaced longitudinally of said board and each pivotally connected to both the base and the top, 50 a brace rod pivoted to said top and having a down-turned lower end, said base having a longitudinal groove formed in its upper surface which retains and guides said down-turned brace end, and said base having a vertical locking recess 55 formed therein at the end of said groove which re-

ceives and holds said brace end, a coil spring centered on a transverse pivotal part of said brace rod and having an extended arm hooked over said brace rod and effective to hold said brace rod with its down-turned end continually pressed into said groove or recess, and an undercut locking member pivotally secured to said base and manually rotatable to engage and hold said down-turned end in said recess and to thereby lock said top in raised ironing position.

10. MAX TRONIC.
